CLAIM

The ornamental design for a top of wall ventilation screed device, as shown and described.

DESCRIPTION

FIG. 1 is a top, front perspective view of a top of wall ventilation screed device showing our new design;

FIG. 2 is a front view of the top of wall ventilation screed device;

FIG. 3 is a back view of the top of wall ventilation screed device;

FIG. 4 is an enlarged right side view of the top of wall ventilation screed device;

FIG. 5 is an enlarged left side view of the top of wall ventilation screed device;

FIG. 6 is a top plan view of the top of wall ventilation screed device;

FIG. 7 is a bottom plan view of the top of wall ventilation screed device; and,

FIG. 8 is a top, rear perspective view of the top of wall ventilation screed device.
